attys.

UNITED STATES PATENT OFFICE.

BERNHARD DIEFENBACH, OF BUFFALO, NEW YORK, ASSIGNOR TO BERNHARD DIEFENBACH AND JAMES D. CAMPBELL, OF BUFFALO, NEW YORK, A PARTNERSHIP, DOING BUSINESS UNDER THE FIRM NAME OF BUFFALO EVERLASTING DISPLAY COMPANY.

METHOD OF MAKING BAS-RELIEFS.

Application filed April 4, 1924. Serial No. 704,273.

To all whom it may concern:

Be it known that I, BERNHARD DIEFENBACH, a citizen of the Republic of Germany, who has signified his intention of becoming a citizen of the United States, residing at Buffalo, in the county of Erie and State of New York, have invented new and useful Improvements in Methods of Making Bas-Reliefs, of which the following is a specification.

The object of the invention is to enable portions of one side of a plate of glass, metal and other material, to be removed by the action of a sand blast in such manner as to economically and rapidly produce a bas-relief of more or less intricate design.

A particular object is to enable portions of one of the layers of a sheet of cameo glass to be quickly, accurately and economically removed by a sand blast, in such manner as to convert the sheet into a cameo having any desired design and adapted to be used for various purposes, and particularly as an advertising sign, which is clearly legible either by reflected light, or by light transmitted through the cameo.

This object is attained by the improved method hereinafter described and claimed.

Of the accompanying drawings forming a part of this specification,

Figure 1 shows in perspective, a portion of a sheet of cameo glass.

Figure 2 is section on line 2—2 of Figure 1.

Figure 3 is a view similar to Figure 1, showing a coating of sensitized paste formed on one of the layers of the glass.

Figure 4 is a section on line 4—4 of Figure 3.

Figure 5 is a side view; and

Figure 6 an edge view of a portion of the pattern hereinafter described.

Figure 7 is a view similar to Figure 4, showing the pattern applied to the paste coating.

Figures 8 and 9 are views similar to Figure 7, on a larger scale, showing the assemblage before and after the sand blast.

Figure 10 shows in perspective, and on a larger scale than Figures 1 to 7, a portion of a completed cameo.

Figures 11 and 12 are views similar to

Figures 8 and 9, illustrating my improved method as practiced in making a bas-relief metal plate.

Figure 13 is a view similar to Figure 12, showing the completed bas-relief after the removal of the hardened portions of the sensitized coating.

The same reference characters indicate the same parts in all of the figures.

In practising the improved method, as illustrated by Figures 1 to 10, a sheet of cameo glass is treated as next described, the sheet being of so-called flash glass, and including a body layer 12, preferably of opal glass, and a facing layer 13 of glass of any desired color, flashed on the body layer, the color of the facing layer contrasting with that of the body layer. One of the layers, preferably the facing layer, is provided with a coating 14, of sensitized paste, which is adherent to glass, is quickly soluble, and is adapted to be rendered more slowly soluble by the action of light.

To the coating 14 is applied a pattern composed of a sheet 15 of thin paper, or other light-transmitting material, and a design formed thereon by India ink, or other material, which is subsequently opaque when applied to the sheet. In the example here shown, the opaque material is designated by 16, and is arranged to form a letter 17, and a border 18, said letter and border being on light-transmitting portions of the sheet.

The design may be of any desired character, and may be more or less intricate. The pattern is preferably caused to adhere to the coating 14 by the adhesiveness of the latter.

The assemblage as shown in section by Figure 7, is next subjected to the action of light, either solar or artificial, the direction of the light being as indicated by the arrow α (Figure 7). The light passing through the light-transmitting portions of the pattern hardens the portions of the sensitized coating not protected by the opaque portions of the pattern, the portions of the coating thus protected being quickly soluble by a solvent such as cold water. The light-hardened portions of the coating are insoluble in cold water, and are soluble in a

different solvent, as hereinafter described. For convenience, I call these portions the hardened portions of the coating, and the others the quickly soluble portions.

5 The pattern and the quickly soluble portions of the coating are next removed by washing, and preferably by submerging the entire assemblage in a bath of cold water, until the pattern is detached and the said 10 soluble portions are dissolved.

A sand blast is then directed, in the direction indicated by the arrow *y* in Figure 8, against the now partially protected glass layer and the hardened portions of the coating 14 remaining thereon, until the exposed portions of said layer are removed and the corresponding portions of the other layer denuded, as shown by Figure 9, other portions of the partially protected glass 20 layer being left intact.

The glass is thus converted into a cameo having relief portions 17^a and 18^a, corresponding to the portions 17 and 18 of the pattern, as indicated by Figure 10.

25 After the application of the sand blast, the hardened portions of the coating may be removed, in any suitable manner, as by immersing the assemblage in a bath of hot water containing ammonia, this bath constituting a solvent of the hardened portions of the coating, which is thus dissolved and removed.

It is obvious that either of the glass layers may be the layer which is acted on by the 35 sand blast. The sensitized paste may be composed of bichromate of potash, two parts, glycerine seven parts, glue twenty-five parts, and water sixty-six parts.

The invention may be practised in making 40 low relief opaque plates suitable for signs and other purposes. For example, the sensitized coating 14 may be applied to one side of a brass sign plate 20 (Figures 11, 12 and 13). After the exposure of the coating to 45 light through the pattern 15, the pattern and the quickly soluble portions of the coating are removed as above described, and the portions of the plate thus exposed are subjected to the action of a sand blast until depressions 50 21 of the desired depth are formed and the plate becomes a bas-relief, after which the hardened portions of the coating are removed as before. The plate 20 may be of any material capable of being cut by a sand 55 blast.

The method may therefore be practised in making a sign or other article which is a cameo adapted to transmit light and differently color the transmitted light, or is an 60 opaque relief plate. It is obvious that the pattern may be provided in any suitable way with light-transmitting portions and opaque portions.

It is essential for the production of a bas- 65 relief having depressions of considerable

depth, and conforming accurately to the pattern, that the coating 14 be applied to the side of the plate facing the source of light, so that the light impinges directly on the exposed outer side of the coating, and its 70 hardening action is uniform from side to side of the coating. The hardened portions of the coating are thus caused to conform accurately to the pattern at each side of the coating, so that the design produced by erosion on the plate also conforms accurately to the pattern, and is not distorted or changed, as would be the case if the pattern were applied to the side of a glass plate 75 opposite the side having the coating. 80

I am aware that it has been heretofore proposed to apply a sensitized coating to one side of a glass plate, and a pattern having opaque and light-transmitting portions to the opposite side of the plate, and out 85 of contact with the coating; the light which acts through the pattern to harden portions of the coating, passing through the glass plate and being spread or diffused in its passage, so that the hardened portions of the 90 coating do not conform accurately to the design of the pattern, because the hardened portions of the coating are enlarged, and the quickly soluble portions correspondingly reduced, in area. Moreover the said plate 95 must be wholly of clear, light-transmitting glass, and cannot be either a plate of cameo glass, including a layer which intercepts light, or a wholly opaque metal plate 20.

My improvement is characterized first by 100 the fact that the pattern is applied to the exposed side of the coating 14, and secondly, by the fact that the light rays are directed against the exposed side of the pattern, and do not pass through the plate, so that the 105 hardened portions of the coating enable the sand blast to accurately reproduce the design of the pattern in the form of depressions of uniform depth, in the coated surface of the plate. 110

What I claim is:

1. The herein described improvement in the method of making a bas-relief, which comprises applying a sensitized coating to a plate, positioning a pattern having light-transmitting and opaque portions adjacent the exposed surface of the sensitized coating, directing light onto said coating through the pattern, removing the portions of the coating which are not affected by the light, and eroding by a sand blast the portions of the plate surface from which said coating has been removed. 115

2. The herein described improvement in the method of making a bas-relief which 120 comprises applying a sensitized coating to one of the layers of a cameo-glass plate, positioning a pattern having light transmitting and opaque portions adjacent the exposed surface of said coating, directing light 125

onto the pattern and portions of said coating exposed therethrough, removing the portions of the coating which are not affected by the light, and cutting through the layers of the 5 plate to which the coating is applied in conformity with the outlines of the portions from which the coating has been removed,

the resulting bas-relief being a cameo presenting different colors either by transmitted or reflected light. 10

In testimony whereof I have affixed my signature.

BERNHARD DIEFENBACH.
